UNITED STATES PATENT OFFICE.

RAYMOND PRESCOTT VIAR, OF LYNCHBURG, VIRGINIA, ASSIGNOR OF ONE-HALF TO
CHARLES W. MCWANE, OF LYNCHBURG, VIRGINIA.

CORE-FORMING DEVICE.

1,373,578.

Specification of Letters Patent.

Patented Apr. 5, 1921.

Application filed July 23, 1919. Serial No. 312,700.

To all whom it may concern:

Be it known that I, RAYMOND PRESCOTT VIAR, a citizen of the United States, residing at Lynchburg, in the county of Campbell 5 and State of Virginia, have invented a new and useful Core-Forming Device, of which the following is a specification.

This invention relates to a core forming device as part of the pattern for making sand molds with cores for iron, steel or other metal castings, said core forming device obviating the necessity of making separate cores of dry sand and placing them in proper position in the mold. 10
15 To those familiar with the art of molding the making of cores as a part of the mold is not new, but the difficulties and drawbacks of the present method of forming such cores are well known.
20 These difficulties are due to the molds being made in two or more parts and the shifting of these parts during their removal from the pattern and plate, frequently making the core defective either from failure to draw it 25 clear from the pattern or to adhere to the mold proper after having been withdrawn from the pattern. Lack of proper means of compressing the sand in the core also frequently results in cutting or crushing of the 30 core by the molten metal, thus rendering the entire casting defective.

The object of this invention is to provide means whereby sand cores can be formed for producing holes in castings, simple and efficient means being utilized whereby the cores are left intact and uninjured by the removal of the mold from the pattern. 35

A still further object is to provide means whereby, in a single mold, cores may be 40 formed for producing openings extending at angles to each other, as in the formation of plow points and the like.

With the foregoing and other objects in view which will appear as the description 45 proceeds, the invention embraces certain novel details of construction and combinations of parts which will be hereinafter more fully described and pointed out in the claims, it being understood that various changes may 50 be made in the construction and arrangement of the parts without departing from the spirit or sacrificing any of the advantages

of the invention as set forth in the appended claims.

In the accompanying drawings the preferred form of the invention has been shown. 55

In said drawings—

Figure 1 is a section through a portion of a flask and the pattern therein, and showing the mechanism employed for controlling the 60 core forming mechanism.

Fig. 2 is a section on line 2—2, Fig. 1.

Fig. 3 is a plan view of the core forming sleeve and of the surrounding portion of the pattern. 65

Fig. 4 is a section through a modified form of mechanism for use in preparing a mold in the casting of plow points.

Fig. 5 is a bottom plan view of the mechanism shown in Fig. 4. 70

Referring to the figures by characters of reference, 1 designates a table adapted to support a pattern 2 and the flask 3 of a mold. An opening 4 is provided in the table and matches an opening 5 in the pattern 2, 75 and secured to the bottom of the table is a bracket 6 having an offset portion 7 extending under the opening 4. A bore 8 is formed in the offset portion 7 in line with the center of the opening 4 and slidably mounted in 80 this bore is the lower end of a pin 9 the upper portion of which projects into the opening 4. A lever 10 is fulcrumed in the bracket 6 and one end projects into a slot 11 in the pin 9 while the other end thereof is 85 connected by a link 12 to a crank arm 13 secured to a shaft 14 which is journaled on the bottom of the table and has an operating arm 15 connected thereto.

Slidably mounted in the openings 5 and 90 4 and upon the pin 9 is a sleeve 16 the upper portion of which constitutes a pattern for a core to be formed by the sand packed within the flask. The lower portion of the sleeve has an angular body 17 which is adapted to 95 slide along one face of the bracket 6 and to be held against rotation thereby. An angular lever 18 is pivotally mounted on the bracket 6 and is pivotally connected to the body 17 by a link 19. An operating lever 100 20 is suspended from the table 1 and is connected to the lever 18 by a link 21.

When the parts are in their normal positions the sleeve 16 is raised with its upper

end flush with the top face of the pattern. 2. The pin is in its lowermost position. Sand is packed about the pattern in the flask and down into the sleeve 16 where it 5 is supported by the upper end of the pin 9. Lever 15 is then operated so as to cause lever 10 to press the pin 9 upwardly within the sleeve and further compress the sand above the pin. While the sand in the sleeve 10 is thus held under compression by the pin the lever 20 is actuated to cause the lever 18 to pull through link 19 upon the sleeve 16 and draw it downwardly along pin 7 and out of the pattern. The core is thereby left 15 intact as the sleeve is drawn from engagement therewith and the flask can be removed, and the casting operation proceeded with. It will be apparent that a number of pins and sleeves can be coupled to one set 20 of levers so that a number of cores can thus be formed simultaneously. Such a duplication of parts is so obvious that a detailed description or illustration thereof is not deemed necessary.

25 In Figs. 5 and 4 has been shown an apparatus for forming a plow point. In this modified structure movable pins are not employed. A bracket 22 is secured under and across the peaked portion of a table 23 and 30 has pins 24 extending at angles therefrom and into openings 25 in the table. The pattern 26 with openings 27 therein is arranged on the table and within the flasks 28 and sleeves 29 are slidably mounted on the pins 35 and project into the opening 27. Each sleeve has an ear 30 extending therefrom and lapping the bracket 22 so as to hold the sleeve against rotation. Levers 31 are pivotally connected to opposite sides of the 40 bracket and one of the levers is connected to one of the sleeves by a link 32 while the other lever is connected by a link 32 to the other sleeve. An arm 33 is connected to the levers and by shifting this arm the two 45 levers are actuated so as to raise or lower the sleeves on the pins 24 thus to set the sleeves or to withdraw them from the formed cores.

What is claimed is:—

50 1. In a core forming device the combination with a structure for supporting a flask and a pattern, of a sleeve member slidably mounted in the pattern and its supporting structure and constituting a core pattern, and means for withdrawing said sleeve

member from the pattern and away from the formed core therein, prior to the removal of the mold from the pattern.

2. In a core forming device the combination with a structure for supporting a flask 60 and a pattern, said structure and pattern having registering openings, of a sleeve mounted in the openings and constituting a core pattern, a pin extending into the sleeve and constituting a core support, and means 65 for shifting the sleeve along the pin to withdraw the sleeve from engagement with the supported core.

3. In a core forming device the combination with a structure for supporting a pattern and having an opening, of a core pattern mounted in the opening, a pin projecting into the core pattern for supporting and guiding said core pattern and means for 70 sliding the core pattern along the pin and 75 from engagement with the core.

4. In a core forming device the combination with a pattern having an opening therein, of a core pattern slidable in the opening, a supporting and guiding pin within 80 the core pattern, means for shifting the pin into the core pattern to compress and support the core, and means for sliding the core pattern along the pin and away from the formed core. 85

5. In a core forming device the combination with a pattern having an opening therein, of a core pattern slidable in the opening, a supporting and guiding pin within 90 the core pattern, and means for shifting the pin within the core pattern to compress the core. 90

6. In a core forming device the combination with a supporting structure and a pattern having registering openings, of a core 95 pattern slidable within the openings, means for holding the core pattern against rotation, a pin slidably mounted in the core pattern, and separate means for shifting the pin and core pattern relative to each other 100 to compress the core within the pattern and to withdraw the core pattern from the core. 100

In testimony that I claim the foregoing as my own, I have hereto affixed my signature in the presence of two witnesses. 105
